UNITED STATES PATENT OFFICE

134,537

DESIGN FOR A DECK OF PLAYING CARDS

Howard W. Buck and Walter T. Neff,
Springfield, Ill.

Application February 23, 1942, Serial No. 106,159

Term of patent 3½ years

To all whom it may concern:

Be it known that we, Howard W. Buck and Walter T. Neff, citizens of the United States and residents of the city of Springfield, county of Sangamon, and State of Illinois, have jointly invented a new, original, and ornamental Design for a Deck of Playing Cards, of which the following is the specification, and reference being had to the accompanying drawings, forming a part thereof.

In the drawings:

Fig. 1 is a face view of the king of hearts.
Fig. 2 is a face view of the queen of hearts.
Fig. 3 is a face view of the jack of hearts.
Fig. 4 is a face view of the king of diamonds.
Fig. 5 is a face view of the queen of diamonds.
Fig. 6 is a face view of the jack of diamonds.
Fig. 7 is a face view of the joker.

Fig. 8 is a face view of the king of spades.
Fig. 9 is a face view of the queen of spades.
Fig. 10 is a face view of the jack of spades.
Fig. 11 is a face view of the king of clubs.
Fig. 12 is a face view of the queen of clubs.
Fig. 13 is a face view of the jack of clubs.
Fig. 14 is a face view of the ace of spades.
Figs. 15, 16, 17, and 18, respectively, are detail views showing the pips, which appear on the remaining cards of the deck.

The remaining cards in this deck that are not shown are conventional except for the pips; and the backs of all these cards are conventional.

We claim:

The ornamental design for a deck of playing cards, as shown and described.

HOWARD W. BUCK.
WALTER T. NEFF.
